UNITED STATES PATENT OFFICE.

DE VER H. WARNER, OF BRIDGEPORT, CONNECTICUT.

DESIGN FOR A BUSTLE.

SPECIFICATION forming part of Design No. 28,275, dated February 8, 1898.

Application filed December 30, 1897. Serial No. 664,744. Term of patent 14 years.

To all whom it may concern:

Be it known that I, DE VER H. WARNER, a citizen of the United States, residing in Bridgeport, in the county of Fairfield and State of Connecticut, have invented and produced a new and original Design for Bustles, of which the following is a specification.

My invention relates to a new and original design for bustles, of which the following is a specification, reference being had to the accompanying drawings.

The drawings represent, in Figure 1, a plan view of a bustle embodying my new design, and in Fig. 2 an end view of the same.

In the drawings, A represents a bustle of a generally crescent configuration, gradually increasing in width from the points B B to-

ward the center. The surface of the bustle is puckered, wrinkled, or corrugated, the corrugations extending radially from the inner ²⁰ to the outer edge. The several corrugations may, it is manifest, be opened at the ends, as at a a a, or closed at the ends, as at b b, as desired.

What I claim is—

The design for a bustle substantially as shown and described.

In testimony whereof I have signed my name to this specification in the presence of two subscribing witnesses.

DE VER H. WARNER. ²⁵
